CLAIM

The ornamental design for a pair of earrings, as shown and described.

DESCRIPTION

FIG. 1 is a top front left perspective view of a pair of earrings, showing my new design;

FIG. 2 is a front elevational view thereof; and,

FIG. 3 is a top rear right perspective view thereof.

The broken lines shown in the drawings represent portions of the pair of earrings that form no part of the claimed design.

1 Claim, 3 Drawing Sheets
